[57] CLAIM

The ornamental design for a buffet, as shown and described.

DESCRIPTION

FIG. 1 is a perspective view of a buffet showing my new design;

FIG. 2 is a front elevational view thereof;

FIG. 3 is a top plan view thereof;

FIG. 4 is a right side elevational view, the left side being a mirror image thereof;

FIG. 5 is an enlarged cross sectional view taken along line 5—5 of FIG. 2;

FIG. 6 is an enlarged detail view of a corner of the buffet taken at circle 6 of FIG. 2; and,

FIG. 7 is an enlarge detail view of a leg of the buffet taken at circle 7 of FIG. 2.
